UNITED STATES PATENT OFFICE.

ERIC SAMUELSON, OF CHICAGO, ILLINOIS, ASSIGNOR TO R. WILLIAMSON & COMPANY, OF CHICAGO, ILLINOIS, A CORPORATION OF ILLINOIS.

LIGHTING FIXTURE.

Application filed October 7, 1925. Serial No. 60,934.

This invention relates to a novel and improved lighting fixture of the type suspended from ceilings. This type of fixture commonly comprises a canopy secured to the ceiling and having suspended therefrom a chain, or the like supporting at its lower end a body having a plurality of arms from which are suspended the lights. Conductors in the form of wires are usually laced 10 through the links of the chain and pass to the interior of the body, the body usually being made of sheet metal and hollow. Various means have been devised to secure the lower end of the chain to the body and also 15 to provide means for passing the wires to the interior of the body. Such means are exemplified by the cross bar, shown in the patent to Ludwig 1,470,855, by the apertured bead and hickey of the patent to Pfeifer 1,504,374, 20 and by the special construction shown in the patent to Robinson 1,487,181. The body is usually built in two portions which are secured together by means of a bolt or the like, the upper end of which is threaded into the 25 loop at the lower end of the chain, or some part carried thereby. It is desirable to have the wires definitely located at this point and concealed from view as much as possible, not only to improve the appearance of the 30 fixture, but also to prevent the wires being disturbed and becoming kinked.

It is therefore the object of my invention to provide means for connecting the loop at the bottom of the chain to the body and also 35 to provide means for properly locating the wires at this point, all of a simplified construction which shall perform the desirable functions achieved by the devices of the aforesaid patents and without the necessity 40 of a hickey or corresponding element.

In the accompanying drawing forming a part of this specification and in which I have shown a selected embodiment of my invention:

45 Fig. 1 is an elevation of a fixture embodying my invention and

Fig. 2 is an enlarged sectional view through the loop.

Referring to the drawing in detail the 50 numeral 1 designates the ceiling of a room to which is secured in the usual manner the canopy 2 having suspended therefrom the chain 3 terminating in the loop 4. The usual

wires 5 are twined through the links of the chain and enter the body designated generally 6 and comprising the upper portion 7 and lower portion 8. Secured to the body are a plurality of arms 9 supporting light sockets 10 in the usual manner.

The loop 4 comprises a base 11 having a 60 bead 12 adapted to contact with the upper surface of the top portion 7 of the body and having a cylindrical portion 13 adapted to enter an opening 14 in the top portion 7. The base terminates in a lug 15 extending 65 slightly within the body and drilled to receive the threaded end of the bolt 16. This bolt extends through the body and has its lower end extending through the lower portion 8 and into the knob 17 which may be 70 made of the usual ornamental appearance. Threaded on the bolt and resting against the upper surface of the lower portion 8 is the nut 18.

Extending diagonally through the base 11 75 is an opening 19, originating at the center 20 of the upper part of the base and terminating to one side of the lower portion thereof, as plainly shown in Fig. 2. This arrangement permits the wires to be brought together at the center of the loop, where they will be least conspicuous and at the same time will dispose them to one side of the bolt 16, which may be retained in the central position where it is most efficient. It will 80 be obvious that this arrangement does away with the necessity for a hickey to receive the bolt and at the same time permits the wires to enter the loop at the center thereof. Therefore, I achieve all the advantages of 85 having the wires enter the loop at the center and also attain all the advantages of the simplified construction in which the hickey is omitted.

I claim:

90 A lighting fixture loop formed with a base having a bead, a cylindrical portion and a lug threaded for cooperation with a bolt, the base and bead having a diagonally-disposed opening extended therethrough upwardly with the lower end terminating free of the said lug and the upper end disposed in substantial vertical alignment with the 95 said lug.

ERIC SAMUELSON.
